UNITED STATES PATENT OFFICE.

STEPHEN C. BURLINGAME, OF STERLING, CONNECTICUT.

BUNDLE-TYING DEVICE.

1,140,246.

Specification of Letters Patent.

Patented May 18, 1915.

Application filed January 8, 1914. Serial No. 811,048.

To all whom it may concern:

Be it known that I, STEPHEN C. BURLINGAME, a citizen of the United States, residing at Sterling, in the county of Windham 5 and State of Connecticut, have invented certain new and useful Improvements in Bundle-Tying Devices, of which the following is a specification, reference being had therein to the accompanying drawing.

10 This invention relates to bundle tying devices and has for its object the production of a simple and efficient sheet-metal clasp over which the several strands of a tie is adapted to be passed and secured thereto for 15 the purpose of efficiently holding the cord or tie in such a manner as to allow the tie or cord to be easily and quickly released.

Other objects and advantages of the present device will appear throughout the following specification and claim.

In the drawings: Figure 1 is a top plan view of the tie showing the same in the first position assumed by the tie when the cord is attached thereto. Fig. 2 is a top plan view 25 of the tie showing a string or cord secured to the clasp, the clasp being shown in its final or locked position. Fig. 3 is a detail perspective of the clasp. Fig. 4 is a detail perspective of the clasp looking at the opposite side from that illustrated in Fig. 3. Fig. 5 is a plan view of the blank from 30 which the clasp is formed. Fig. 6 is a longitudinal section through the fastener.

By referring to the drawing, it will be 35 seen that 1 designates the body portion of the clasp which is provided with a pair of oppositely-extending lips 2, which lips have their outer ends slightly outwardly curved to facilitate the entrance of a cord between 40 the lip and the body portion 1. The fastener is formed of a blank sheet of material and when folded will assume a substantially Z-shaped structure. Each of the lips 2 is provided with an overhanging or outwardly-folded tongue 3, which tongue has 45 its outer end slightly turned upwardly so as to facilitate the entrance of a string or cord under the tongue. The tongues 3 are carried by each lip 2 near the folded portion of 50 the lip, or, in other words, near the junction of the lip and the body portion of the fastener. When the fastener is in a folded position, it will be seen that one tongue will be carried upon both the top and bottom of 55 the fastener.

From the foregoing description, it will be seen that, owing to the construction of the device, the fastener may be formed of a minimum amount of material and may also be stamped in one operation of a machine. 60

In actual operation, the fastener may be grasped between the thumb and fore-finger to facilitate the placing of the end of a cord 4 under the tongue 3 upon the top of the fastener as shown at 6. The cord is then 65 placed under the top lip 2 as indicated at 7 and the fastener is then placed upon the article desired to be wrapped, having the cord extending away from the hand as shown at 8 in Fig. 1. The cord is then 70 wound around the package 5 to be wrapped to the position shown in Fig. 1. The portion of the cord as indicated at 9 in Fig. 2 is then continued around at right-angles to the cord illustrated in Fig. 1 at 8 until the 75 cord assumes the position shown in Fig. 2, whereupon the fastener is turned over toward the right and the free end 10 of the cord is then passed under the upper lip, which previously was the lower lip and the 80 free end 10 of the cord is then placed under the free tongue 3 illustrated in Fig. 2, which previously was the lower lip 3, thereby firmly holding the cord in a set position upon the package. It will be understood 85 that the fastener is turned over in the position shown in Fig. 2 relative to the position of the fastener in Fig. 1, thereby showing the reverse side or what was previously the under-side of the fastener illustrated in 90 Fig. 1.

What is claimed is:

A package tie comprising a fastener formed from a blank sheet of material having a body portion terminating at its opposite ends in backwardly-bent, oppositely-extending, outwardly-curved lips, each lip provided with a backwardly-folded tongue-portion extending from the side edge of said lip adjacent the junction of the lip with the 95 body portion of the fastener and adapted to receive a cord for holding the same in a set position.

In testimony whereof I hereunto affix my signature in presence of two witnesses.

STEPHEN C. BURLINGAME.
